VACUUM TUBE CIRCUIT FOR OPERATING
RELAYSMadison G. Nicholson, Jr., Snyder, N. Y., assignor
to Colonial Radio Corporation, Buffalo, N. Y.

Application April 19, 1944, Serial No. 531,807

10 Claims. (Cl. 175—320)

1

This invention relates to a new and improved circuit for operating relays, and more particularly, circuits of the kind wherein the plate current of a vacuum tube, flowing through a solenoid, mechanically opens or closes one or more relay contacts.

In electrical work, there are many occasions where it is desired to utilize a control voltage to cause the operation of a relay. As a typical example of the problem to which my invention is addressed, assume that a control voltage is applied between the grid and cathode of a three-element vacuum tube in such a manner as to make the grid negative with respect to the cathode. Connected in the plate circuit of such a tube there may be the operating winding of a relay which is to open when the control voltage equals —50 volts. Assume also that the only tube available is one in which the plate current reaches a value at which the relay opens when the grid voltage is —10 volts with respect to the cathode.

It will be clear that if the control voltage is applied directly to the grid and cathode of the tube, the relay will not operate properly, but will open when the control voltage equals —10 volts, whereas it should stay closed until the control voltage equals —50 volts. This premature operation of the relay will cause malfunctioning of the circuits depending upon it. In the past, under such conditions, it has been customary to provide a voltage divider between the control voltage source and the cathode and control grid of the tube.

In the example above given, if it is desired to have the relay open at —50 volts, a 5 to 1 voltage divider would be employed to reduce the control voltage; that is, the cathode and control electrode would be connected across $\frac{1}{5}$ of the total resistance of the voltage divider.

With such an arrangement the voltage between the cathode and grid of the tube will always be $\frac{1}{5}$ of the control voltage and will never drop to 0 unless the control voltage drops to 0. Stated somewhat differently, as the control voltage increases negatively from 0 to —50 volts, the negative voltage on the tube increases and the plate current is cut down; that is, the tube characteristics are being employed to vary the space current for any changes in voltage from 0 to —50.

Thus, with a control voltage of —25 volts, the plate current might be sufficiently reduced so that a slight jar would knock the relay open and the plate current would not be sufficiently strong to close it, because somewhat more current is re-

quired to move the relay from open to closed position than to hold it in closed position.

Greatly improved operation may be obtained if the tube can be made to operate more like an on-off switch; that is to say, in the example given, an improvement in operation would be obtained if the plate current stayed at maximum while the control voltage moved from 0 to —40, and thereafter dropped toward cutoff as the control voltage moved from —40 to —50. This improvement is possible using the circuits of this invention.

Among the objects of my invention are the following:

To provide a relay circuit whose operating characteristics are less susceptible to variations resulting from change in tube characteristics.

To provide a circuit which will effectively alter the operating characteristics of any particular vacuum tube to make it fit the control voltages desired to be employed.

To provide a circuit of the class described in which an available vacuum tube may be arranged to operate efficiently with control voltages which would otherwise not be adapted for use with the tube.

To provide a circuit of the class described in which the opening and closing of the relay is made more definite and certain.

To provide a circuit of the class described in which the operation of the relay may be made more definite from the standpoint of time and also with respect to control voltage.

Still other objects and advantages of my invention will be apparent from the specification.

35 In this application I have particularly pointed out and distinctly claimed the part, improvement, or combination which I claim as my invention or discovery, and I have explained the principles thereof and the best mode in which I have contemplated applying those principles so as to distinguish my invention from other inventions.

In the drawing,

Fig. 1 is a circuit diagram of one form of circuit in accordance with my invention.

45 Fig. 2 is a similar view of a modified form, and Figs. 3, 4, and 5 are curves explaining the operation of my invention.

In the example given, employing the same tube and relay, greatly improved operation can be obtained utilizing the circuit of Fig. 1, wherein 50 12 may represent a thermionic vacuum tube having cathode 12c, control grid 12g, and anode 12a. The control voltage may be applied across the input terminals T1 and T2, T1 being connected 55 to the grid through biasing battery 10 and re-

sistor 11. The plate circuit may comprise the winding 13 of relay 14, resistor 15, and may be completed through the usual B source.

In this figure, a 5 to 1 improvement in relay operation in terms of variation of characteristics of the tube and relay may be obtained by employing battery 10, so poled as to make the control electrode 12g positive with respect to the cathode, and having a voltage of 40 volts. Resistance 11 is preferably of a substantial value; for example, one megohm, so as to effectively limit grid current. Under these conditions it will be clear that the grid will remain positive at all times and the tube will be drawing its maximum current until the control voltage is more negative than -40 volts.

The plate current will remain constant until the control voltage passes beyond -40 volts in the negative direction, whereupon it will begin to decrease and the relay will open at -50 volts, at which time the grid will be at -10 volts; that is to say, the tube varies the relay current only in the last 10 volts of change of the control voltage, and a jar which in the former instance would have opened the relay and caused malfunctioning of the relay controlled circuits will not now affect the relay over the range from 0 to -40 volts.

Under certain conditions it is undesirable to employ biasing batteries, and this may be particularly true in case the plate supply is obtained from a power pack. Under such circumstances the circuit of Fig. 2 may be employed, wherein like characters represent the same elements as in Fig. 1, but in this instance I may employ a resistor 15 in series with a B battery supply and a relay winding, and may provide a connection from the B supply through additional resistor 16 to the control grid 12g.

In this example, it is desired that the voltage drop through resistor 11 be the same as before; i. e., -40 volts; and, therefore, the B supply current flowing through resistance 11 should be .04 milliamper. The resistance of 11 plus 16 will, therefore, be so related to plate voltage as to give this current according to the well-known formula $E=IR$.

If the plate supply voltage is 400 volts, the control voltage 50 volts, and 11 one megohm, then resistance 16 will be 10.25 megohms, this producing the required voltage drop of 40 volts in 11. The action of the circuit may be more clearly understood with reference to Fig. 3, in which curve A represents the characteristics of the tube in terms of plate current plotted against control voltage.

If the control voltage were applied directly to the grid from 0 to -50 volts, it would be apparent that after it has reached -10 volts, the relay has opened and nothing happens for any further increase in control voltage in the negative direction, as shown by curve A. Curve B shown may represent plate current of the tube for varying control voltage when the control voltage is applied to the tube through a 5 to 1 voltage divider, and it will be observed that plate current now decreases from its maximum for any negative control voltage and that very substantial decreases in plate current occur for drops in control voltage which are not desired to open the relay.

Curves C and D may represent the operation of the circuit shown in Figs. 1 and 2 for different values of bucking voltage from battery 10 or resistor 11, and it will be observed that by appropriate choice in value of this bucking voltage, operation of the tube (drop from maximum

current to opening) may be made to occur within any 10 volts variation in control voltage. Curves B and C are drawn to scale for the same operating voltage; i. e., 50 volts, and C represents the improvement which my invention affords.

While for purposes of clarity of disclosure I have used the example of 50 volts control voltage and 10 volts operating voltage on the grid of the tube, it should be understood that this is only by 10 way of example, and that the same principles may be applied for different values of control voltage and operating voltage.

The circuit of Fig. 1 has the characteristic that the required operating voltage to open or close the relay is for all practical purposes independent of the plate supply voltage over a wide range of plate voltage, as indicated in Fig. 4. Thus, this circuit is of particular value in cases where it is desired that the operating point be practically 20 constant with a wide range of plate supply voltage.

On the other hand, the circuit in Fig. 2 has the characteristic that the required operating or control voltage to open or close the relay is approximately proportional to the plate supply voltage, as will be seen from Fig. 5. Such a characteristic is useful when it is desired that the operating voltage be proportional to the supply voltage. This is frequently the case where the tube or 30 tubes (not shown) furnishing the control voltage have their plate circuits fed from the same source that supplies the plate circuit of tube 12.

While I have shown and described certain preferred embodiments of my invention, it will be understood that modifications and changes may be made without departing from the spirit and scope of my invention, as will be apparent to those skilled in the art.

I claim:

1. Electrical apparatus, comprising, in combination, a thermionic tube having a cathode, an anode, and a control electrode, and a source of anode-cathode current supply, a relay having an energizing winding connected in the space current path of said tube, a source of potential difference and a resistor connected in series between said cathode and control electrode with a polarity to impress a positive bias on said control electrode, and means for impressing a control voltage 40 between said cathode and control electrode with a polarity to make said control electrode negative with respect to said cathode, said energizing winding being normally energized over a substantial portion of the range of variation of the control voltage, the magnitude of the positive biasing voltage being somewhat less than the control voltage for which said relay is to be released, and the magnitude of the positive biasing voltage being so related to the control voltage and to the characteristics of the tube that the range of spurious operation due to vibration and jar is greatly reduced.

2. Electrical apparatus, comprising, in combination, a thermionic tube having a cathode, an anode, and a control electrode, and a source of anode-cathode current supply, a relay having an energizing winding connected in the space current path of said tube, a source of potential difference and a resistor connected in series between said cathode and control electrode with a polarity to impress a positive bias on said control electrode, and means for impressing a control voltage 65 between said cathode and control electrode with a polarity to make said control electrode negative with respect to said cathode, said energizing winding being normally energized over a substantial portion of the range of variation of the control voltage, the magnitude of the positive biasing voltage being somewhat less than the control voltage for which said relay is to be released, and the magnitude of the positive biasing voltage being so related to the control voltage and to the characteristics of the tube that the range of spurious operation due to vibration and jar is greatly reduced.

energizing winding being normally energized over a substantial portion of the range of variation of the control voltage, the magnitude of the positive biasing voltage being so related to the control voltage for which said relay is to operate that maximum space current is passed by said tube over a substantial portion of the range of variation of the control voltage, the magnitude of the positive bias being somewhat less than the magnitude of the control voltage for which the relay is to be released, and the magnitude of the positive biasing voltage being so related to the control voltage and to the characteristics of the tube that the range of spurious operation due to vibration and jar is greatly reduced.

3. Electrical apparatus, comprising, in combination, a thermionic tube having a cathode, an anode, and a control electrode, and a source of anode-cathode current supply, a relay having an energizing winding connected in the space current path of said tube, a source of potential difference and a resistor connected in series between said cathode and control electrode with a polarity to impress a positive bias on said control electrode, and means for impressing a control voltage between said cathode and control electrode with a polarity to make said control electrode negative with respect to said cathode, said energizing winding being normally energized over a substantial portion of the range of variation of the control voltage, the magnitude of the positive biasing voltage being somewhat less than the control voltage for which said relay is to be released, and the value of said resistor being sufficiently large as to substantially prevent the flow of grid current, and the magnitude of the positive biasing voltage being so related to the control voltage and to the characteristics of the tube that the range of spurious operation due to vibration and jar is greatly reduced.

4. Electrical apparatus, comprising, in combination, a thermionic tube having a cathode, an anode, and a control electrode, and a source of anode-cathode current supply, a relay having an energizing winding connected in the space current path of said tube, a source of potential difference and a resistor connected in series between said cathode and control electrode with a polarity to impress a positive bias on said control electrode, and means for impressing a control voltage between said cathode and control electrode with a polarity to make said control electrode negative with respect to said cathode, said energizing winding being normally energized over a substantial portion of the range of variation of the control voltage, the magnitude of the positive biasing voltage being so related to the control voltage for which said relay is to operate that maximum space current is passed by said tube over a substantial portion of the range of variation of the control voltage, and the value of said resistor being sufficiently large as to substantially prevent the flow of grid current, the magnitude of the positive bias being somewhat less than the magnitude of the control voltage for which the relay is to be released, and the magnitude of the positive biasing voltage being so related to the control voltage and to the characteristics of the tube that the range of spurious operation due to vibration and jar is greatly reduced.

5. Electrical apparatus, comprising, in combination, a thermionic tube having a cathode, an anode, and a control electrode, and a source of anode-cathode current supply, a relay having an

energizing winding connected in the space current path of said tube, a source of potential difference and a resistor connected in series between said cathode and control electrode with a polarity to impress a positive bias on said control electrode, and means for impressing a control voltage between said cathode and control electrode with a polarity to make said control electrode negative with respect to said cathode, said energizing winding being normally energized over a substantial portion of the range of variation of the control voltage, the magnitude of the positive biasing voltage being somewhat less than the control voltage for which said relay is to be released, said last means comprising a connection including a resistance, from said control electrode to said source of anode-cathode current supply, and the magnitude of the positive biasing voltage being so related to the control voltage and to the characteristics of the tube that the range of spurious operation due to vibration and jar is greatly reduced.

6. Electrical apparatus, comprising, in combination, a thermionic tube having a cathode, an anode, and a control electrode, and a source of anode-cathode current supply, a relay having an energizing winding connected in the space current path of said tube, a source of potential difference and a resistor connected in series between said cathode and control electrode with a polarity to impress a positive bias on said control electrode, and means for impressing a control voltage between said cathode and control electrode with a polarity to make said control electrode negative with respect to said cathode, said energizing winding being normally energized over a substantial portion of the range of variation of the control voltage, the magnitude of the positive biasing voltage being so related to the control voltage for which said relay is to operate that maximum space current is passed by said tube over a substantial portion of the range of variation of the control voltage, said last means comprising a connection including a resistance, from said control electrode to said source of anode-cathode current supply, the magnitude of the positive bias being somewhat less than the magnitude of the control voltage for which the relay is to be released, and the magnitude of the positive biasing voltage being so related to the control voltage and to the characteristics of the tube that the range of spurious operation due to vibration and jar is greatly reduced.

7. Electrical apparatus, comprising, in combination, a thermionic tube having a cathode, an anode, and a control electrode, and a source of anode-cathode current supply, a relay having an energizing winding connected in the space current path of said tube, a source of potential difference and a resistor connected in series between said cathode and control electrode with a polarity to impress a positive bias on said control electrode, and means for impressing a control voltage between said cathode and control electrode with a polarity to make said control electrode negative with respect to said cathode, said energizing winding being normally energized over a substantial portion of the range of variation of the control voltage, the magnitude of the positive biasing voltage being somewhat less than the control voltage for which said relay is to be released, and the value of said resistor being sufficiently large as to substantially prevent the flow of grid current, said last means comprising a connection including a resistance, from said control electrode

to said source of anode-cathode current supply, and the magnitude of the positive biasing voltage being so related to the control voltage and to the characteristics of the tube that the range of spurious operation due to vibration and jar is greatly reduced.

8. Electrical apparatus, comprising, in combination, a thermionic tube having a cathode, an anode, and a control electrode, and a source of anode-cathode current supply, a relay having an energizing winding connected in the space current path of said tube, a source of potential difference and a resistor connected in series between said cathode and control electrode with a polarity to impress a positive bias on said control electrode, and means for impressing a control voltage between said cathode and control electrode with a polarity to make said control electrode negative with respect to said cathode, said energizing winding being normally energized over a substantial portion of the range of variation of the control voltage, the magnitude of the positive biasing voltage being so related to the control voltage for which said relay is to operate that maximum space current is passed by said tube over a substantial portion of the range of variation of the control voltage, and the value of said resistor being sufficiently large as to substantially prevent the flow of grid current, said last means comprising a connection including a resistance, from said control electrode to said source of anode-cathode current supply, the magnitude of the positive bias being somewhat less than the magnitude of the control voltage for which the relay is to be released, and the magnitude of the positive biasing voltage being so related to the control voltage and to the characteristics of the tube that the range of spurious operation due to vibration and jar is greatly reduced.

9. Electrical apparatus, comprising, in combination, a thermionic tube having a cathode, an anode, and a control electrode, and a source of anode-cathode current supply, a relay having an energizing winding connected in the space current path of said tube, a source of potential difference and a resistor connected in series between said cathode and control electrode with a polarity to impress a positive bias on said control electrode, and means for impressing a control voltage between said cathode and control electrode with a polarity to make said control electrode negative with respect to said cathode, said energizing winding being normally energized over a substantial portion of the range of variation of the control voltage, the magnitude of the positive biasing voltage being so related to the control voltage for which said relay is to operate that maximum space current is passed by said tube over a substantial portion of the range of variation of the control voltage, and the value of said resistor being sufficiently large as to sub-

- stantially prevent the flow of grid current, said last means comprising a connection including a resistance, from said control electrode to said source of anode-cathode current supply, said 5 thermionic tube and the tube which furnishes the control voltage having a common source of space current, the magnitude of the positive bias being somewhat less than the magnitude of the control voltage for which the relay is to be released, and 10 the magnitude of the positive biasing voltage being so related to the control voltage and to the characteristics of the tube that the range of spurious operation due to vibration and jar is greatly reduced.
- 15 10. Electrical apparatus, comprising, in combination, a thermionic tube having a cathode, an anode, and a control electrode, a relay having an energizing winding connected in the space current path of said tube, a source of potential difference and a resistor connected in series between 20 said cathode and control electrode with a polarity to impress a positive bias on said control electrode, and means for impressing a control voltage between said cathode and control electrode with 25 a polarity to make said control electrode negative with respect to said cathode, said energizing winding being normally energized over a substantial portion of the range of variation of the control voltage, the magnitude of the positive 30 biasing voltage being so related to the control voltage being somewhat less than the magnitude of the control voltage for which the relay is to be released and for which said relay is to operate that maximum space current is passed by said 35 tube over a substantial portion of the range of variation of the control voltage, and the value of said resistor being sufficiently large as to substantially prevent the flow of grid current, said last means comprising a connection including a 40 resistance, from said control electrode to said source of anode-cathode current supply, a single source of plate current for said thermionic tube and the control tube, whereby the control voltage is substantially proportional to plate voltage, and 45 the magnitude of the positive biasing voltage being so related to the control voltage and to the characteristics of the tube that the range of spurious operation due to vibration and jar is greatly reduced.
